UNITED STATES PATENT OFFICE.

JOSEPH F. LAURIN, OF ATTLEBOROUGH, MASSACHUSETTS, ASSIGNOR TO
THE JAMES E. BLAKE COMPANY, OF SAME PLACE.

DESIGN FOR A HANDLE FOR SPOONS, FORKS, &c.

SPECIFICATION forming part of Design No. 30,169, dated February 14, 1899.

Application filed January 21, 1899. Serial No. 702,994. Term of patent 7 years.

To all whom it may concern:

Be it known that I, JOSEPH F. LAURIN, of Attleborough, in the county of Bristol and State of Massachusetts, have invented and produced a new and original Design for the Handles of Spoons, Forks, and Similar Articles, of which the following is a specification, reference being had to the accompanying drawings, forming part thereof.

Figure 1 is a representation of a handle attached to the bowl portion of a spoon and illustrates my new design, the tine portion of a fork being shown in dotted lines. Fig. 2 represents a reverse view of the same.

The leading features of my design consist in the design as herein shown and described.

In the drawings, 3 represents the handle, and 4 the bowl of a spoon. It may, however, represent any similar article, one of which is indicated in the drawings. The outline of the handle extends upward from the article to which it is attached in symmetrical curving lines, gradually expanding the width of the handle to 5, then contracting and expanding to 6, and then gradually curving outward and inward by the curves 7 and 8 to the shell ornament 9 at the top.

The obverse side of the handle, Fig. 1, is ornamented by the raised beads 10 10, the beaded scrolls 11, the foliated scrolls 12 12, 30 the beaded scrolls 13 13, the balls 14 14, the shell ornament 9, and the central floral ornament 15.

The reverse side of the handle, Fig. 2, is ornamented by the raised beads 21 21, the beaded scrolls 22 22, the foliated scrolls 23 23 and 24 24, the shell ornament 25 at the top, the small scrolls 26 26, surrounding the panel 27, and the floral pendant 28.

Having thus described my invention, what I claim as new, and desire to secure by Letters Patent, is—

The design for the handle of a spoon, fork or similar article as herein shown and described.

In witness whereof I have hereunto set my hand.

JOSEPH F. LAURIN.
